United States Patent Office.

RICHARD GRIMM, OF NEW YORK, N. Y.

Letters Patent No. 99,430, dated February 1, 1870.

IMPROVED SPRING MOTOR.

The Schedule referred to in these Letters Patent and making part of the same.

To all whom it may concern:

Be it known that I, RICHARD GRIMM, of the city, county, and State of New York, have invented a new and improved Spring-Motor; and I do hereby declare the following to be a full, clear, and exact description thereof, which will enable those skilled in the art to make and use the same, reference being had to the accompanying drawing, forming part of this specification, in which drawing—

Figure 1 is a side view of the invention.

Figure 2 is an elevation of the apparatus, which shows a side view of the pulleys, to which motion is communicated by the motor.

Similar letters indicate corresponding parts.

This invention relates to a mechanical motor, in which the power is obtained from the tension put upon a spring; and

It consists in a peculiar construction and arrangement of parts, whereby simplicity and economy of construction are obtained in this class of motors.

The letter A designates a frame, by which the apparatus is supported, and in which the several shafts have their bearings.

To the upper part of the frame, on its under side, I secure a stout spring, B, of the description sometimes called a C-spring, composed of any desired number of leaves, a b c d, according to the power required, the inner leaves being successively shortened in length, and all being secured to the frame at their centre, by a bolt, C.

The extremities of the spring B are drawn together by cords D D, which are fastened at one end to said extremities, while their other ends are attached to a winding-pulley, E, placed within the spring B, on a shaft, F, which is turned by means of a crank G.

The pulley E can be grooved, and can be conical, or of the kind known as a fusee; but I do not confine myself to any mode of making said pulley.

As the shaft F is turned, the cords D D are wound

up on the pulley, and the ends of the spring B are drawn toward each other, so as to put the desired tension or compression on the spring.

Upon the shaft F I place the first wheel H of a train of gear-wheels, by which I cause the resistance or power of the spring to be communicated to the pulleys.

The wheel H is loose on the shaft F, and is connected to said shaft by a spring-pawl and ratchet-wheel, in the usual manner, which allows the spring to be compressed without motion being given to said wheel.

The other wheels in the train, marked I J, are constructed and combined in the mode common in watch and clock movements, and the last wheel in the train, the wheel J, engages a worm, K, on the shaft L, on which is fixed a pulley, M, which will be driven at a speed commensurate to the tension of the spring, and the work to be performed by said pulley. The power thus obtained is distributed to other shafts, by means of bands and pulleys, as illustrated by the band and pulley N O, shown in fig. 2.

I strengthen the spring B, and give it additional stiffness and elasticity, by means of a counter or supplemental spring P, which I arrange below it, so as to form a counterpart thereto, the ends of the supplemental spring being connected to the ends of spring B by means of the cords D D.

What I claim as new, and desire to secure by Letters Patent, is—

The C-spring B, the cords D D, and winding-pulley F, combined, arranged and operating substantially as described, through a train of gear-wheels, with a worm-wheel, K, on the driven shaft L.

This specification signed by me, this 7th day of December, 1869.

RICHARD GRIMM.
